UNITED STATES PATENT OFFICE.

JAMES M. BOLTON, OF WASHINGTON, DISTRICT OF COLUMBIA.

MOLD FOR BUILDING-BLOCKS.

No. 826,467.

Specification of Letters Patent.

Patented July 17, 1906.

Application filed October 17, 1905. Serial No. 283,119.

To all whom it may concern:

Be it known that I, JAMES M. BOLTON, a citizen of the United States, residing at Washington, in the District of Columbia, have invented certain new and useful Improvements in Molds for Building-Blocks, of which the following is a specification, reference being had to the drawings, in which—

Figure 1 is a plan showing the mold assembled. Fig. 2 is an end elevation of the same; Fig. 3, an inside view of one of the side members; Fig. 4, a cross-section on the line IV IV, showing the mold closed; and Fig. 5, a section along the same line, showing the mold partly opened.

My invention relates to molds for building-blocks, preferably such as are made in the form of an ordinary brick, having apertures which may be alined in the laying to furnish flues to prevent the accumulation of moisture, the blocks being preferably composed of a mixture of cement and coarsely-granulated slag or gravel and having a thin facing of substantially pure cement or of cement combined only with coloring material to give the appearance of a tile, my object being to provide a cheap and easily-constructed separable mold in which this facing may be readily and rapidly applied to one side and, if desired, one end of the block before it is removed from the mold and while the latter provides guiding edges for the trowel or other tool.

In the drawings, 1 is a base, whose width is substantially the length of a block, long enough to hold a number of blocks and upon which the blocks may be set away to dry when the molding is completed. This base has, preferably, a facing 1' of some non-corrosive metal, such as sheet-brass.

Upon the base may be assembled the inclosing sides 2 2', the former being as wide as the width of the block plus the thickness of the base and the latter preferably only as wide as the width of the block to be molded, as shown in Figs. 2, 4, and 5. When assembled, these sides are supported by tenons on the ends 3, passing into grooves or mortises 3', as shown in Figs. 1 and 3. These parts are then secured by hooked clamps 7, seating in the notches 7', and apertured partitions 4, preferably of metal of suitable thickness, are dropped into the grooves 9 of the sides 2 2'.

The partitions are preferably provided at one lower corner with hooks or tongues 4', which engage recesses 6 at the bottoms of the grooves 9 of the wider side member. They

are also slightly recessed, as at 10, to prevent binding when the member 2 assumes the position shown in Fig. 5.

After the above-described parts are assembled the mold may be filled to about the level of the lower edge of the registering apertures 5', and the core 5, which is preferably U-shaped, is passed through the apertures, as shown in Fig. 1, after which the filling, tamping, and striking of the mold is completed.

It will be noted that the parts are so proportioned that the upper edges of the sides, ends, and partitions of the mold lie in substantially the same plane, so that a thin facing of cement or other suitable material may be applied to the upper edge of each block and troweled or otherwise finished, using the mold members as guides.

If it is desired to finish an end of each block with a facing of finer material, as may be necessary in molding corner-blocks, core 5 and clamps 7 are removed and the side member 2 swung outward about its lower edge as a fulcrum to the position shown in Fig. 5, thus releasing the member 2' and bringing the free ends of the partitions 4 just "flush" with the edge of the base 1 and the ends of the molded blocks. This exposes the ends of the blocks so that the finer facing may be applied and smoothed, while the partitions still remain in place as guides for the finishing-tool. The length of the hooks 4' may be so proportioned that member 2 will disengage itself therefrom just as the opposite ends of the partitions are brought into register with the free edge of the base and the exposed ends of the blocks. After the ends of the blocks have been faced, as above described, the partitions may be completely removed and the base, with its contained blocks, set aside till the latter have hardened sufficiently to be safely handled.

Many variations in my apparatus may be made by those skilled in the art without departing from my invention, since

What I claim is—

1. A block-mold having partitions and means for automatically withdrawing and then releasing the partitions when the mold is opened.

2. A separable block-mold having inclosing sides, partitions and separable connections between said sides and partitions arranged to partially withdraw the partitions when the mold is opened.

3. A separable block-mold having a base, inclosing sides and ends, and partitions, said

ends being constructed to support the sides in proper relation to the base, and connections between the partitions and one side, arranged to automatically withdraw the partitions a predetermined distance, when the mold is opened.

4. A separable block-mold having sides, partitions having apertures, a core adapted to be inserted in said apertures, and connections between one of said sides and the partitions for partially withdrawing the partitions after the core is removed.

5. A separable block-mold comprising a base, inclosing sides, apertured partitions

and a core adapted to be inserted in said apertures, the upper edges of the sides and partitions lying in substantially the same plane, clamps for holding said sides and partitions in closed position, and means for automatically withdrawing the partitions a predetermined distance when the mold is opened.

In testimony whereof I affix my signature in presence of two witnesses.

JAMES M. BOLTON.
